UNITED STATES PATENT OFFICE.

PAUL TRABUE AND LYMAN TRABUE, OF GIRARD, ILLINOIS.

TENSION-BAND FOR BALING-PRESSES.

SPECIFICATION forming part of Letters Patent No. 728,516, dated May 19, 1903.

Application filed February 27, 1903. Serial No. 145,363. (No model.)

To all whom it may concern:

Be it known that we, PAUL TRABUE and LYMAN TRABUE, citizens of the United States, residing at Girard, in the county of Macoupin and State of Illinois, have invented certain new and useful Improvements in Tension-Bands for Baling-Presses, of which the following is a full, clear, and exact description, reference being had to the accompanying drawings, forming part of this specification.

Our invention relates to bands surrounding the boxes of baling-presses for service in applying tension to the friction-walls of the press-boxes; and the invention consists in features of novelty hereinafter fully described, and pointed out in the claims.

Figure I is a perspective view of a baling-press box with our band applied thereto. Fig. II is a transverse section taken on line II II, Fig. I, and showing parts of the tension-band in elevation.

A designates the top, and B the bottom, of the baling-press box, and C designates the side friction-walls of the box. The friction-walls C are located between angle-strips D, secured to the top and bottom of the press-box.

1 designates cross-bars extending transversely of the top and bottom of the press-box. These cross-bars are of channel form in cross-section for the purpose of affording a maximum of strength. The cross-bars 1 are bifurcated at their ends and project beyond the edges of the top and bottom of the press-box to receive the pivotal connection of single links 2 through means of bolts 3, passed through the ends of the cross-bars and said links.

4 designates bifurcated nuts, in which the links 2 are seated and held by pivot-bolts 5.

6 designates tension-screws positioned in the bifurcated nuts 4, with which they have threaded engagement.

7 designates pressure-bars fixed to the friction-walls C and provided centrally with sockets 8, that receive the inner ends of the tension-screws 6. The pressure-bars 7 are provided with arms 9, which extend beyond the main bodies of the bars into proximity

with the angle-strips D, attached to the top 50 and bottom of the press-box.

10 designates pocket-brackets fixed to the angle-strips D and in which the pressure-bar arms 9 are seated and guide in the movement of said bar inwardly and outwardly in 55 acquiring the desired positioning of the friction-walls C. Each of the pocket-brackets is formed with side walls 11, that serve to direct the arms 9 in their movement to prevent lateral strain on the pressure-bars, while at 60 the same time the arms being confined between the bases of the brackets endwise movement of the pressure-bars either upwardly or downwardly is obviated.

By the construction herein described we 65 provide a tension-band of very simple and effective form and one that can be easily and readily afforded to apply power for tension on all sides of the press-box, the only action necessary to obtain said tension being the 70 movement of the tension-screws 6 to adjust the pressure-bars 7 and at the same time exert a pull upon the top and bottom cross-bars through the medium of the connecting-links 2 and bifurcated nuts 4. 75

We claim as our invention—

1. The combination with a baling-press box, comprising a top and bottom and yielding friction-walls, of cross-bars applied to the top and bottom of the box and having bifurcated ends, single links pivoted in the bifurcated ends of said cross-bars, bifurcated nuts connecting said links, pressure-bars fixed to said friction-walls, and tension-screws seated in said bifurcated nuts and adapted to bear 85 against said pressure-bars, substantially as set forth.

2. The combination with a baling-press box having a top and bottom and friction side walls, pocket-brackets secured to the top and bottom of said box, pressure-bars secured to said friction-walls and having arms positioned in said pocket-brackets, cross-bars applied to the top and bottom of the press-box, links pivoted to said cross-bars, nuts connecting 90 said links, and tension-screws seated in said nuts to bear against said pressure-bars, substantially as set forth.

3. The combination with a baling-press box having a top and bottom and friction side walls, pocket-brackets secured to the top and bottom of said box and having side guide-walls, pressure-bars secured to said friction-walls and having arms positioned in said pocket-brackets, cross-bars applied to the top and bottom of the press-box, links pivoted to said cross-bars, nuts connecting said links,

and tension-screws seated in said nuts to bear ~~to~~ against said pressure-bars, substantially as set forth.

PAUL TRABUE.
LYMAN TRABUE.
